E. W. MARVEL

AUTOMATICALLY OPERATIVE CONTROLLING MECHANISM FOR HEATERS

Original Filed May 26, 1920

FIG. I

FIG. II

FIG. III

FIG. IV

FIG. V

FIG. VI

FIG. VII

INVENTOR:

EDWARD WILLEY MARVEL,

*Edward E. Marvel,
Attorney.*

UNITED STATES PATENT OFFICE.

EDWARD WILLEY MARVEL, OF PHILADELPHIA, PENNSYLVANIA.

AUTOMATICALLY-OPERATIVE CONTROLLING MECHANISM FOR HEATERS.

Application filed May 26, 1920, Serial No. 384,250. Renewed June 12, 1923.

To all whom it may concern:

Be it known that I, EDWARD WILLEY MARVEL, a citizen of the United States, residing at Philadelphia, in the county of Philadelphia and State of Pennsylvania, have invented a certain new and useful Improvement in Automatically-Operative Controlling Mechanism for Heaters, whereof the following is a specification, reference being had to the accompanying drawing.

Ordinarily, the gas supply to the several burners of a cooking range is only manually controlled by individual gas cocks local to the respective burners so that in order to prevent waste of gas it is necessary for the operator to turn the gas on or off in correspondence with placing utensils on or off of the range; a precaution which is frequently neglected. Therefore, it is an object and effect of my invention to provide means to automatically control the supply of gas to a burner in accordance with whether the burner is in use or not. As hereinafter described, such control is effected by providing a valve mechanism in such position that it is automatically operated to admit gas to the burner, when a cooking utensil, sadiron, or other device is placed in position to use the heat from the burner and, when said heat using device is removed, the supply of gas is automatically shut off or diminished by the operation of said valve mechanism consequent upon the movement of said heat using device. That is to say; if the burner is provided with a pilot light, my invention may be so adjusted as to entirely shut off the supply of gas to the main burner and leave only the pilot light burning and, if the burner is not provided with a pilot light, my device may be so adjusted as to merely lower the flame to a minimum degree sufficient to maintain it; of course, subject to the usual control of the manually operative stop cocks aforesaid whereby the supply may be entirely shut off. Moreover, as hereinafter described, my invention may be so constructed and arranged as to be operated by the opening and closing of an oven door. That is to say; it may be arranged to increase the supply of gas when the oven door is shut and decrease or entirely shut off the supply of gas when the oven door is opened, in accordance with the condition to which the device is adjusted.

My invention includes the various novel

features of construction and arrangement hereinafter more definitely specified.

In said drawing; Fig. I is a fragmentary, sectional view of a gas range having convenient embodiments of my invention applied thereto viz, one shown in operative relation with a frying pan and another indicated in operative relation to an oven door.

Fig. II is a fragmentary plan view, partly in section, showing two valve bodies such as are indicated in Fig. I, each including both the manually operative valve and an automatically operative valve controlling the gas supply to the burner, local thereto.

Fig. III is a detached perspective view of said automatically operative valve, provided with the sectoral lever plate by which it is arranged to be operated.

Fig. IV is a fragmentary perspective view of the end of the tappet lever adjacent said automatic valve, showing its detachable pivotal connection whereby said sectoral plate is operatively engaged when in the position shown in Fig. I.

Fig. V is a perspective view of the detachable clamp ring indicated in Fig. I encircling the burner tube, upon which said tappet lever is fulcrumed.

Fig. VI is a perspective view of the stop device carried by said tappet lever in Fig. I and adjustable to variably limit the opening movement of said automatically operative valve.

Fig. VII is a perspective view of the detachable counterbalance weight which is adjustably connected with said tappet lever shown in Fig. I.

The gas range which is indicated in Fig. I is provided with the usual top frame 1 adapted to uphold removable plates 2 arranged to support heat using devices, such as the frying pan 3, in operative relation with the gas flame 4 extending above the burner 5 which extends beneath said plates 2 in registry with the opening 6 therein. Said burner 5 is provided with the usual gas supply tube 7 having the bell inlet 8 with a perforated cap 9 to admit air around the gas nozzle 10. Said nozzle is at the inner end of the valve body 11 which is connected with the gas supply pipe 12. Said valve body holds the ordinary plug stop cock 14 which is arranged to be manually operated by the handle 15, and also the auxiliary valve 17 which is provided with the sectoral lever plate 18, whereby it may be

operated as hereinafter described. As shown in Fig. II; said valve plug 14 has a port 20 extending therethrough which is adapted to register with the passage 21 in said valve body 11, or not, in accordance with the position to which said handle 15 is turned. Said valve 17 likewise has the gas port 23 which is adapted to register with said gas passage 21, or not, in accordance with the position to which said valve 17 is turned. I prefer to make said port 23 of the circumferentially tapered form indicated in Fig. III, so that the volume of gas flowing therethrough may be adjustably varied to a greater degree than if said port were circular. Such a tapered port may be conveniently formed by drilling a circular hole through said valve plug 17 and filing one edge thereof.

Said valve 17 may be conveniently operated by the tappet lever 25 which is fulcrumed upon the screw 26 carried by the clamp ring 27. As best shown in Fig. V, said clamp ring 27 is split at 28 so that it may be clamped upon said burner tube 7, by said fulcrum screw 26 which engages the nut 29. I also prefer to provide said clamp ring 27 with a set screw 30 having a pointed inner end to engage a corresponding depression in said tube 7 so that when said clamp ring 27 is secured in the position shown in Fig. I it may not be accidentally displaced. Said tappet lever 25 is conveniently provided at its outer end with the detachable screw 32, best shown in Fig. IV, which is adapted to form a pivotal connection with said sectoral plate 18, by being selectively engaged with any one of the slots 34 in said plate; so that, when said lever 25 is tilted downwardly at its inner end, said plate 18 is turned upwardly and said valve 17 correspondingly turned to open said gas passage 21. The extent of such tilting movement of said lever 25 may be precisely limited by the stop device shown in Fig. VI, including the fitting 35 which is adjustably secured by the set screw 36 upon said lever 25 and carries the stop screw 37 which abuts against the edge of said clamp ring 27. The weight 39, best shown in Fig. VII, is provided with the set screw 40 so that it may be adjustably connected with said lever 25, as shown in Fig. I, so as to normally shift said lever to its lowermost position to automatically turn said valve 17 and close said passage 21; but the inner end of said lever 25 is adapted to be depressed by any heat using device set there-over, so as to thus automatically open said valve 17 whenever any such device is placed in position to use the heat generated by said flame 4.

However, as some forms of pots and pans and other heat using devices are hollow at the bottom, I find it convenient to provide

the inner end of said tappet lever 25 with means to adjustably vary its effective height with respect to the top plates 2 of said range. For instance, as shown in Fig. I, said lever may be provided with the adjustable screw 41 which may be rotated to raise it to encounter a cooking utensil with a hollow bottom or be lowered to encounter a utensil having a flat bottom, such as said frying pan 3.

Moreover, my invention is conveniently adapted to be operated by the door 43 of the oven 45, by providing said sectoral plate 18 with the extension 46; so that a valve 17 such as above described, when located in front of said door, presents said extension 46 in position to be encountered by said door when it is lowered to its open horizontal position and thus connects the valve 17 of the burner in operative relation with the oven, without the employment of said tappet lever 25.

Although I have described my invention as applied to an ordinary gas burner, it is to be understood that it is equally applicable to any heater, regardless of the nature of the heating medium, to automatically control the use of the latter as above described.

Therefore, I do not desire to limit myself to the precise details of construction and arrangement herein set forth, as it is obvious that various modifications may be made therein, without departing from the essential features of my invention as defined in the appended claims.

I claim:

1. The combination with a gas burning heater having a support for removable articles to be heated; of a burner extending beneath said support; a rotary valve constructed and arranged to control the flow of gas to said burner, in accordance with its turning movement; and means, including a tappet lever operatively related to said valve and normally projecting from said support, but capable of being displaced to open said valve, by an article placed on said support in position to be heated; and an oven, having a door arranged to close said valve when said door is opened.

2. The combination with a gas burning heater; of a valve constructed and arranged to control the supply of gas to said heater, including a rotary conical plug, a sectoral lever plate on said plug, a series of radial slots in said lever plate, and a tappet lever having an arm provided with an adjustable member arranged to be selectively engaged with anyone of said slots; said lever having another arm presented in position to be displaced by an article to be heated; whereby said valve is opened when an article to be heated is placed in position to be heated, and the degree of opening movement is predeter-

mined by the selective engagement of said tappet lever with said sectoral lever.

3. The combination with a gas burner; of a valve constructed and arranged to control the supply of gas to said burner, including a rotary conical plug having a gas port which is tapered circumferentially, in cooperative relation with a port leading to said burner; whereby a gradual increment and decrement in the effective area of said port is consequent upon the turning movement of said valve plug; a lever plate rigidly connected with said plug; an oven having a door arranged to directly engage and

turn said plate and plug; and a tappet lever, 15 carrying means arranged to selectively engage said lever plate, and having an arm whereby said tappet lever is displaced to operate said valve when an article to be heated is placed in cooperative relation with 20 said burner.

In testimony whereof, I have hereunto signed my name at Philadelphia, Pennsylvania this fifth day of May, 1920.

EDWARD WILLEY MARVEL.
